FLOAT VALVE PULLER

Boyd E. Hine, Lewistown, Mont.

Application July 8, 1952, Serial No. 297,671

1 Claim. (Cl. 294—90)

This invention relates to float valve pullers, and particularly to devices for removing float valves from drill pipe strings. It is customary, in drilling wells by rotary apparatus, to drive the rotary bit by means of a string of pipe or tubing to which the bit is fastened. It is also customary to provide a valve structure adjacent the lower end of the drill string to prevent upward movement of liquids in the interior of the pipe. It is often necessary to remove those valves from the pipe string for replacement or repair.

The present invention is directed particularly to a device for removing valves of the type commonly known in the trade as a "Baker" float valve assembly. The valve assembly referred to is merely pushed into a counterbore at the lower end of the pipe and is retained therein by the drill bit. Often during use of such valves they become stuck in the pipe and adhere to the counterbore sufficiently to render it extremely difficult to remove them by hand methods.

The present invention is directed to a device to be engaged with a diametrically extending spider in the valve assembly whereby power may be applied to forcibly remove the valve. The puller of the present invention consists generally of a pair of legs joined together at one end and having transverse hook-like members at their free ends adapted to engage the spider with the joined ends of the legs projecting outwardly of the pipe in which the valve is located. Fixed to the joined ends of the legs is a means that may be engaged by a chain or other anchoring instrumentality. In use, the drill pipe is pulled from the well and suspended in the derrick by means of the usual draw works a short distance above the rotary platform. In such position a valve puller may be engaged with the valve and anchored to the floor of the rig by the aforementioned chain. The draw works may then be actuated to pull upwardly on the pipe whereupon the chain and valve puller, being anchored to the floor, will effect forcible withdrawal of the valve assembly from the drill string.

It is, therefore, an object of this invention to provide an improved valve puller.

Another object of the invention is to provide a valve puller wherein its grip on the valve assembly is made more firm as greater force is applied.

Another object of this invention is to provide an efficient valve puller of rugged construction, yet simple and economical to produce.

A still further object of this invention is to provide a valve puller having twisted and pre-stressed tension members whereupon the application of pulling force to the members results in a tendency to untwist and thereby increase their grip on the valve assembly.

Still another object of the invention is to provide a valve puller readily adapted to be actuated by power means.

Additional objects and advantages will appear to those skilled in the art as the description proceeds in connection with the accompanying drawings, wherein:

Fig. 1 is a fragmentary sectional view of a drill string

2

pipe showing a float valve therein but with the drill bit removed;

Fig. 2 is a side elevational view of a valve puller constructed in accordance with the present invention;

5 Fig. 3 is a transverse sectional view taken along the line 3—3 of Fig. 2 but showing, in dotted line, the relationship of the hooking elements to the device;

Fig. 4 is a perspective view of the puller of Fig. 2;

Fig. 5 is an enlarged sectional view similar to Fig. 1 10 but showing the valve puller and anchor chain in their position of use; and

Fig. 6 is a view similar to Fig. 2, but of a modified form of the invention.

Fig. 1 shows a drill string pipe 2 having a central opening 4 therethrough and a counterbore 5 at its lowermost end defining a shoulder 6. The terminal end of the pipe 2 is provided with a tapered threaded portion 8 adapted to receive a rotary drill bit of conventional construction. Within the counterbore 5 is a cylindrical body 10 comprising the body portion of a float valve. The body 10 may be provided with suitable packing or sealing means 12. Within the upper portion of the valve body a valve seat (not shown) is formed and engaged by a valve member (not shown) having a stem 14 guided in a suitable bearing 16. The bearing 16 is supported in a diametrically extending bridge or spider 18 within the body 10. The body 10 and, in fact, the entire valve structure, may be inserted as a unit in the counterbore 5 by merely pushing same therein into abutment with the shoulder 6. 20 Subsequent assembly of the rotary bit to the threaded portion 8 effects retention of the valve assembly in the pipe. After a period of use the body 10 often becomes stuck to the walls of the counterbore and thereby rendered difficult to remove by manual means.

35 The valve puller for effecting forcible removal of the valve assembly from the pipe 2 is shown in Fig. 2. The puller consists of an anchor means which, as shown, consists of a ring 20 fixed to the upper end of a pair of legs 22 and 24. The legs 22 and 24 have lower substantially parallel portions and upper converging portions 26 and 28 joined together and to the anchor ring 20 at a central location, such as at 30. It is to be noted that the junction 30 lies between the legs 22 and 24. The legs 22 and 24 are provided at their free ends with arcuate and laterally extending hooking elements 32 and 34. Each of the elements 32 and 34 extends generally laterally of a plane defined by the legs 22 and 24 and each is arcuately curved, as indicated in Figs. 3 and 4, to present its concave side to the other hooking element. Each hooking element is 40 also provided with an upper surface 36 facing the joined ends of the legs and preferably lying in a common plane. Each of the legs 22 and 24 is further characterized by being 45 twisted about its longitudinal axis as indicated in Fig. 2 at 38 and clearly shown in Figs. 3 and 4. The direction of the twist applied to each leg is such as to move the free end of its associated hooking element away from the other leg of the device. The twist is sufficient to permanently 50 distort the legs and stress the material thereof.

55 It is to be understood that the material from which the device is constructed is a resilient material, preferably of a high modulus of elasticity, such as steel. Each of the legs 22 and 24 is preferably of rectangular section, as shown in Fig. 3, but may, in fact, be of any desired sectional shape.

60 In use in the manner previously described, the valve puller is inserted upwardly into the lower end of body 10 (see Fig. 5) and positioned so that the surfaces 36 engage the uppermost edge of the bridge or spider 18 with the legs 22 and 24 on opposite sides of the spider. Fig. 5 65 also shows the anchoring chain 40 engaging the ring 20 of the puller. With the parts in the position shown in Fig. 5,

the draw works of the drilling rig may be actuated to exert an upward pull on pipe 2, as indicated by the arrow at the top of the figure, and since the valve puller is anchored to the floor of the rig, the puller and valve assembly are prevented from moving upwardly with the pipe. Sufficient power may be applied to effect withdrawal of the valve assembly from the counterbore 5.

If a substantial pull is required to dislodge the valve assembly, the legs 22 and 24 will be quite highly stressed in tension and, having been pre-twisted in the manner and direction described, the tension will tend to cause them to at least partially return to their original or untwisted condition, thereby moving the ends of the hooking elements toward each other to effect a more secure grip on the bridge or spider 18 and prevent accidental disengagement. It is also to be noted that the tension in chain 40 is applied to the valve puller at point 30 whereas the vertical forces acting on the hooking elements 32 and 34 are laterally displaced from a line of action passing through point 30, thus introducing a bending moment in the legs 22 and 24, tending to move the hooking elements toward each other in addition to the twisting effect previously described.

A modified form of valve puller is shown in Fig. 6 wherein the ring 20 is omitted and legs 22' and 24' constitute the end portions of a single generally U-shaped structure having a bight at 42. The bight constitutes means that may be engaged by a hooked chain such as shown at 40 in Fig. 5 to anchor the device to the floor of the rig. It will be obvious that the puller of Fig. 6 will respond to stresses exactly in the same manner as described in connection with the form shown in Fig. 5.

While a single embodiment of the invention has been

specifically shown and described herein, it is to be understood that the disclosure is merely illustrative. It is contemplated that the invention include other modifications which may fall fairly within the scope of the appended claim.

I claim:

A float valve puller comprising: a unitary bifurcated member of resilient material having spaced apart leg portions rigidly joined together at one end at a central juncture, means rigid with said leg portions at said juncture for engaging an anchor member, the other end of each of said leg portions having a laterally extending hooking element formed thereon, said hooking elements extending in opposite directions transverse to a plane containing said legs and each being provided with a transverse surface facing the said one end, each of said leg portions being twisted generally about its longitudinal axis in a direction to move its hooking element away from the other leg portion whereby tension in said legs causes said hook elements to pivotally move toward each other by the tendency of said leg portions to untwist resiliently under the influence of said tension.
